US0D1038032S

(12) United States Design Patent (10) Patent No.: US D1,038,032 S
Ren et al. (45) Date of Patent: * Aug. 6, 2024

(54) CAR WIRELESS ADAPTER

(71) Applicant: Yiwu Nansheng E-commerce Co., LTD, Yiwu (CN)

(72) Inventors: Pan Ren, Yiwu (CN); Yuhui Zhang, Yiwu (CN)

() Term: 15 Years

(21) Appl. No.: 29/925,077

(22) Filed: Jan. 22, 2024

(51) LOC (14) Cl. 13-02

(52) U.S. Cl.

USPC D13/108

(57) CLAIM

We claim the design for a car wireless adapter, as shown and described.

DESCRIPTION

FIG. 1 is a perspective view of a car wireless adapter showing our new design.

FIG. 2 is a second perspective view thereof.

FIG. 3 is a front view thereof.

FIG. 4 is a rear view thereof.

FIG. 5 is a left side view thereof.

FIG. 6 is a right side view thereof.

FIG. 7 is a top view thereof; and,

FIG. 8 is a bottom view thereof.

The broken lines depict portions of the article that form no part of the claimed design.

1 Claim, 8 Drawing Sheets
